(57) **CLAIM**

The ornamental design for a covering for a fragrance diffuser, substantially as shown.

DESCRIPTION

FIG. 1 is a perspective view of a covering for a fragrance diffuser with multiple diffusion wicks, according to a first embodiment;

FIG. 2 is a front view of the covering for a fragrance diffuser with multiple diffusion wicks, according to the first embodiment;

FIG. 3 is a rear view of the covering for a fragrance diffuser with multiple diffusion wicks, according to the first embodiment;

FIG. 4 is a right side view of the covering for a fragrance diffuser with multiple diffusion wicks, according to the first embodiment;

FIG. 5 is a left side view of the covering for a fragrance diffuser with multiple diffusion wicks, according to the first embodiment;

FIG. 6 is a top view of the covering for a fragrance diffuser with multiple diffusion wicks, according to the first embodiment;

FIG. 7 is a bottom view of the covering for a fragrance diffuser with multiple diffusion wicks, according to the first embodiment;

FIG. 8 is a perspective view of a covering for a fragrance diffuser with multiple diffusion wicks represented by broken lines, according to a second embodiment;

FIG. 9 is a front view of the covering for a fragrance diffuser with multiple diffusion wicks represented by broken lines, according to the second embodiment;

FIG. 10 is a rear view of the covering for a fragrance diffuser with multiple diffusion wicks represented by broken lines, according to the second embodiment;

FIG. 11 is a right side view of the covering for a fragrance diffuser with multiple diffusion wicks represented by broken lines, according to the second embodiment;

FIG. 12 is a left side view of the covering for a fragrance diffuser with multiple diffusion wicks represented by broken lines, according to the second embodiment;

FIG. 13 is a top view of the covering for a fragrance diffuser with multiple diffusion wicks represented by broken lines, according to the second embodiment; and,

FIG. 14 is a bottom view of the covering for a fragrance diffuser with multiple diffusion wicks represented by broken lines, according to the second embodiment.

The covering for a fragrance diffuser material is an opaque or translucent polymer material and blocks the view of the bottle containing aromatic liquid.

The broken line elements in all views are for illustrative and environmental purposes only and form no part of the claimed design.
